Clarence E. Threedy
INVENTOR

UNITED STATES PATENT OFFICE

104,297

DESIGN FOR AN AMUSEMENT MACHINE CABINET

Clarence E. Threedy, Chicago, Ill., assignor to
H. M. Butterworth and O. M. Hoag, Chicago,
Ill.

Application February 13, 1937, Serial No. 67,637

Term of patent 3½ years

To all whom it may concern:

Be it known that I, Clarence E. Threedy, a citizen of the United States and a resident of Chicago, in the county of Cook and State of Illinois, have invented a new, original, and ornamental Design for an Amusement Machine Cabinet, of which the following is a specification, reference being had to the accompanying drawing, forming a part thereof, and in which:

Fig. 1 is a perspective view of the amusement machine cabinet showing my new design; and
Fig. 2 is a top plan view of the same.

I claim:

The ornamental design for an amusement machine cabinet, as shown.

CLARENCE E. THREEDY.
